PRESSURE-INDICATING MEANS

Joseph A. Chyba, Baltimore, Md., assignor to
Hydro-Form Corporation, Baltimore, Md., a
corporation of Maryland

Application March 3, 1948, Serial No. 12,872

9 Claims. (Cl. 18—19)

1

This invention relates to a pressure-indicating means for a shape-forming device, and has for one of its objects the production of a simple and efficient means for facilitating the control of pressure in the shape-forming device relative to the distance of travel of the die counter to said pressure.

A further object of this invention is the production of a pressure-control means in association with a shape-forming device for facilitating the regulation of the pressure in the shape-forming device in proportion to the distance of travel of the shape-forming die and at the same time indicating to the operator the distance of travel of the die and the pressure which is being maintained counter to the movement of the die.

Other objects and advantages of the present invention will appear through the following specification and claims.

In the drawings:

Figure 1 is a diagrammatic view of the pressure-indicating means and associated parts;

Figure 2 is an enlarged plan view of the travel dial which indicates the distance of travel of the shape-forming die;

Figure 3 is a transverse sectional view, partly in elevation, of the operating mechanism and dial shown in Figure 2;

Figure 4 is a horizontal sectional view taken on line 4—4 of Figure 3; and

Figure 5 is a bottom plan view of a portion of the rack-carrying casing, illustrating the tension means for the gear-carrying shaft.

By referring to the drawings, it will be seen that 10 designates the dome of the shape-forming device which is provided with a pressure cavity or compartment or chamber 11. The compartment 11 is closed by a flexible diaphragm 12. Any type of diaphragm may be employed without departing from the spirit of the invention. A die-carrying member 13 is suitably mounted on a platform 14 and the die 15 is movable into contact with the worksheet 16 which work sheet is in turn initially held against the diaphragm 12 by the die 15. The die 15 is actuated by means of the mechanism 17 of the conventional type to force the die 15 against the flexible diaphragm 12, and counter to the pressure in the compartment or chamber 11.

A depending link 18 which is connected to the die-actuating mechanism 17 of the die 15, extends below the cylinder 19. A flexible cable 20 or other die-connecting means is secured to the link 18 and this cable 20 preferably passes over suitable guiding pulleys 21. A rack bar 22 is

2

connected to the opposite end of the cable or connecting means 20, as shown in Figure 1. A tension spring 22a is connected to the opposite end of the rack bar 22 and is suitably anchored to prevent lost motion and hold the cable 20 and rack bar 22 under a tension at all times.

A suitable supporting plate 23 is conveniently mounted to support the dial 24 and the pressure gage 25 in a position to be easily viewed by an operator. The pressure gage 25 is of the conventional type except that the pressure-indicating disc or dial 26 is keyed to the conventional pointer supporting shaft, as at 27, and rotates with said shaft to rotate the pressure disc or dial 26 relative to the index 28 which is interposed between the dial 24 and the disc 26 to indicate the amount of pressure in the chamber 11 at all times. The pressure gage 25 is connected to the supply line 29 by means of a suitable pipe 30. The cavity or compartment 11 of the dome 10 is connected to the supply line 29 by means of a flexible connection 31 of any suitable type to permit of proper movement of the dome 10. The supply line 29 is connected to the supply pump 32 by a suitable connecting pipe 33 and an automatic check valve 34 and a manually controlled valve 35 are interposed between the pump 32 and line 29. A pipe 36 forms a connection between a suitable reservoir and the supply pump 32. A pressure return pipe 37 carries a suitable needle valve 38 and leads from the pipe 29 at a point beyond the pipe 30 to the reservoir to return the pressure fluid to the reservoir when desired and when the apparatus is not in use.

It should be noted that I do not make any claim to the type of valve or pump used, since conventional types are employed without departing from the spirit of the invention.

As shown in Figure 3, the supporting plate 23 supports a rectangular casing 39 which is suspended therefrom by suitable screws 40. The casing 39 is provided with a longitudinal channel 41 and an operating shaft 42 extends vertically through the channel 41 and is journaled intermediate its ends in the supporting plate 23 and at its lower end in the casing 39. A gear 43 is fixed to the shaft 42 and fits in the channel 41 in a position to mesh with the teeth of the rack bar 22. A suitable gib or other securing means 44 overhangs the rack bar 22 to hold the bar in meshing relation with the gear 43. The shaft 42 is provided with a dial-supporting head 45 at its upper end to which the dial 24 is se-

cured or anchored by means of suitable screws 46 so as to rotate with the shaft 42.

The head 45 is provided with an upstanding neck 47 upon which neck an indicating hand 48 is rotatably mounted. A reduced threaded stem 49 is carried by the upper end of the neck 47. A flat compression spring 49 engages the hand 48 and fits around the neck 47. A nut 50 is threaded upon the neck 47 and contacts the spring 49 to clamp the spring 49 into frictional engagement with the hand 48 to lock the same against the spacer washer 51 and hold the hand 48 in a set position relative to the dial 24. A knob 52 is carried by the hand 48 to facilitate the rotation of the hand 48 to the desired setting on dial 24. A bead 53 near the periphery of the dial 24 preferably supports the outer end of the hand 48. A pulley 54 is keyed to the lower end of the shaft 42 below the casing 39. A tension coil spring 55 is secured at one end to the pulley 54 and partly extends theraround, the opposite end of the spring 55 being anchored at 56 to return the shaft 42 to its normal position when pulling power is released from the rack bar 22.

It should be noted that the disc or dial 26 is graduated in the conventional manner, as is common with pressure dials and as indicated on the drawings. The dial 24 is graduated, as at 24^a in inches and fractions thereof, with a slight overplay to indicate the distance of travel of the die 15 against the pressure on the diaphragm 12. The rack 22 and gear 43 function in relation to the travel of the piston and die, these parts being out of sight. Since the distance of travel of the die and the pressure in the chamber 11 must be known at all times for proper operation of the device, the operator will be able to visualize the distance of travel of the die and the amount of pressure in the chamber 11 by observing the positions of the dials 24 and 26 relative to the index 28. The desired distance of travel of the die or piston may be initially set by moving the hand 48 to the desired reading on the dial 24. When the set hand 48 which is locked on the dial 24 registers with the index 28 against the counteracting pressure shown on the pressure gage 25, the operator knows that the proper shape has been formed in the shape-forming device. The pressure may be regulated by the operator by actuating the valve 35 to increase or decrease the pressure as registered on the disc 26 relative to index 28. When the selected pressure on the gage disc 26 registers with the index 28 at the same time the selected distance on the dial 24 as indicated by the hand 48 registers with said index 28, the operator knows that the machine has properly functioned to produce the desired shape of work intended to be produced. It is obvious that as the die and piston travel upward against the diaphragm 12, the liquid or air in the compartment or chamber 11 is compressed and will vary at different elevations, consequently the manually-operated relief valve 35 is operated to relieve or allow the head pressure to build up to a selected degree as indicated by the disc 26 relative to the index 28.

It should be noted that the movement of the dial 24 is properly synchronized with the movement of the die through the medium of the gear 43 and rack 22, to indicate distance of travel by the die in inches and fractions thereof.

Having described the invention, what is claimed as new is:

1. In combination with a shape-forming de-

vice of the class described having a pressure chamber, a flexible diaphragm movable into said pressure chamber, a movable shape-forming die adapted to shape a blank sheet against said flexible diaphragm; a movable indicator, means connecting the indicator to the movable die for registering the distance of movement of said die against said diaphragm, and a pressure gage connected to said pressure chamber for indicating the amount of pressure in said chamber.

2. In combination with a shape-forming device of the class described having a pressure chamber, a flexible diaphragm movable into said pressure chamber, a movable shape-forming die adapted to shape a blank sheet against said flexible diaphragm; a movable indicator, means connecting the indicator to the movable die for registering the distance of movement of said die against said diaphragm, a fixed index adjacent said indicator to facilitate the reading of said indicator, and a pressure gage also registering with said index and connected to said pressure chamber for indicating the amount of pressure in said chamber.

3. In combination with a shape-forming device of the class described having a pressure chamber, a flexible diaphragm movable into said pressure chamber, a movable shape-forming die adapted to shape a blank sheet against said flexible diaphragm; a movable indicator, means connecting the indicator to the movable die for registering the distance of movement of said die against said diaphragm, a fixed index adjacent said indicator to facilitate the reading of said indicator, a pressure gage also registering with said index and connected to said pressure chamber for indicating the amount of pressure in said chamber, a source of pressure supply leading to said chamber and said gage, and valve means for regulating and varying pressure in said chamber as said die moves against said diaphragm and into said chamber.

4. In combination with a shape-forming device of the class described having a pressure chamber, a flexible diaphragm movable into said pressure chamber, a movable shape-forming die adapted to shape a blank sheet against said flexible diaphragm; a movable indicator, means connecting the indicator to the movable die for registering the distance of movement of said die against said diaphragm, said indicator comprising a graduated movable indicator element, and a rack and pinion connected to and interposed between the indicator element and said last mentioned means for indicating the movement of said die, the movement of the indicator element being synchronized with a movement of said die.

5. In combination with a shape-forming device of the class described having a pressure chamber, a flexible diaphragm movable into said pressure chamber, a movable shape-forming die adapted to shape a blank sheet against said flexible diaphragm; a rotatable indicator, means connecting the indicator to the movable die for registering the distance of movement of said die against said diaphragm, said indicator comprising a graduated rotatable indicator plate, and a rack and pinion connected to and interposed between the indicator plate and said last mentioned means for indicating the movement of said die, the movement of said indicator plate being synchronized with the movement of said die.

6. In combination with a shape-forming device of the class described having a pressure chamber, a flexible diaphragm movable into said

pressure chamber, a movable shape-forming die adapted to shape a blank sheet against said flexible diaphragm; a rotatable indicator, means connecting the indicator to the movable die for registering the distance of movement of said die against said diaphragm, said indicator comprising a graduated rotatable indicator plate, a rack and pinion connected to and interposed between the indicator plate and said last mentioned means for indicating the movement of said die, the movement of said indicator plate being synchronized with the movement of said die, and said plate being graduated in inches and fractions thereof to designate the distance of travel of the rack and die.

7. In combination with a shape-forming device of the class described having a pressure chamber, a flexible diaphragm movable into said pressure chamber, a movable shape-forming die adapted to shape a blank sheet against said flexible diaphragm; a rotatable indicator, means connecting the indicator to the movable die for registering the distance of movement of said die against said diaphragm, said indicator comprising a graduated rotatable indicator plate, a rack and pinion connected to and interposed between the indicator plate and said last mentioned means for indicating the movement of said die, the movement of said indicator plate being synchronized with the movement of said die, said plate being graduated in inches and fractions thereof to designate the distance of travel of the rack and die, a movable indicator hand mounted upon said plate, means for locking said hand in a selected position to indicate desired selected distance of movement of said die, and a fixed index adjacent said indicator plate.

8. In combination with a shape-forming device of the class described having a pressure chamber, a flexible diaphragm movable into said

pressure chamber, a movable shape-forming die adapted to shape a blank sheet against said flexible diaphragm; a movable indicator, means connecting the indicator to the movable die for registering the distance of movement of said die against said diaphragm, a fixed index adjacent said indicator to facilitate the reading of said indicator, and a pressure gage having a rotating graduated plate also registering with said index for indicating the amount of pressure in said chamber.

9. In combination with a shape-forming device of the class described having a pressure chamber, a flexible diaphragm movable into said pressure chamber, a movable shape-forming die adapted to shape a blank sheet against said flexible diaphragm; a movable indicator, means connecting the indicator to the movable die for registering the distance of movement of said die against said diaphragm, a fixed index adjacent said indicator to facilitate the reading of said indicator, a pressure gage having a rotating graduated plate also registering with said index for indicating the amount of pressure in said chamber, a source of pressure supply for said chamber, and a control valve for varying the pressure in said chamber in proportion to the distance of movement of said die relative to said diaphragm.
